UNITED STATES PATENT OFFICE.

FREDERICK WILLIAM VICKERY, OF LONDON, ENGLAND.

PAPER-FEEDING MACHINE FOR PRINTING OR LIKE MACHINES.

No. 857,426.

Specification of Letters Patent.

Patented June 18, 1907.

Application filed December 11, 1903. Serial No. 184,822.

To all whom it may concern:

Be it known that I, FREDERICK WILLIAM VICKERY, a subject of the King of Great Britain, residing at 13 St. Ann's Villas, Notting Hill, London, England, have invented certain new and useful Improvements in or Connected with Paper-Feeding Machines for Printing or Like Machines, of which the following is a specification.

10 The object of my invention is to construct an appliance capable of being connected to any sheet printing machines, whereby the top sheet of the pile of paper is positively released from contact with its neighboring sheet before leaving the pile to be fed into the machine and is kept from contact during the feed.

My invention is illustrated in the annexed drawings—Figure 1 being a side elevation of 20 a paper feeding machine with one side frame and a number of the operative parts for actuating the air box removed; Fig. 2 is a plan view of Fig. 1; Fig. 3 is a fragmentary view partly in section of the automatic cut-off in 25 the air supply pipe; Fig. 4 is a top view thereof; Fig. 5 is a side view of a portion of a machine on an enlarged scale showing the mechanism for actuating the movable air box; Fig. 6 is a similar view from the other side of 30 the machine and showing the gearing for operating the movable air box; Fig. 7 is an enlarged view of the arms situated over the pile of paper and their means of suspension; Fig. 8 is a front view of the arms with the fingers 35 detached.

In the drawings *a* designates the usual frame of a printing machine, and *b*, *b* are standards attached to or forming part of said frame, these standards carrying a rising and 40 falling feed table *c* supported by bars *d* sliding vertically in the uprights of the standards *b*, *b*. These features form no part of my present invention, and therefore need not be further explained herein. For the purpose 45 of my invention I make a hollow box or pipe *e*, or the like, and perforate same along one side or edge as at *f*. This box or pipe *e* is in connection by a tube *g* with a fan, pump or like device actuated from the printing machine, or a separate appliance.

The perforated box *e* is mounted on rocking arms *h*, *h* which are fixed on an oscillating

shaft *i*, actuated by a cam or other suitable mechanism, the shaft imparting to the box *e* an up-and-down or rocking motion, and such mechanism is in connection with or carries suitable appliances such as a hit and miss valve or a tap for turning off the supply of air to the perforations *f* when the box *e* is at or approaching the lower end of its movement. In Fig. 1 said box *e* is shown at its lowest position, and, consequently, the air supply is nearly closed. The perforated box *e* can be fitted on either or all sides of the pile of paper as circumstances require, and moves in unison with the feed, that is to say, the pipe or box *e* commences to rise just before the feed roller *j* is commencing to operate on the pile of paper *k*, and in so doing the air valve or tap is opened, and the air passes to 70 the perforations *f* to impinge against the edge of the pile of paper which it does and so to speak opens out the edge of each sheet as shown in dotted lines, the sheets being retained in position by arms as will be herein-after explained, and on the arrival of the perforated box *e* at its highest position in dotted lines as at Fig. 1 to have full action upon the upper set of sheets, and where there is the least resistance. The roller *j* is moved 75 around the axle *p* and just before it commences to reach the pile of paper the air box *e* has risen and the blast of air has impinged against the edges of the sheets and passed air between them so as to separate or form a 80 film of air between said sheets, the latter being held by the bars *q*. When the air box *e* is at its highest point the roller *j* has just reached the paper. However, it will be apparent the air box and roller *j* when lowering 85 move together and the said air box being just in advance of said roller *j*, the latter pressing the opened out sheet back on to the pile while the continued movement will grip the top sheet and by reason of it being opened out pass it along off the pile and over the air box *e* until its front edge reaches the band *v* and suspended rollers 27 between which the sheet will be gripped and carried down the band *v* by the movement of the latter. 90

During the passage of the roller *j* over the pile of paper and the air box *e* the knuckle-jointed arm 28 carrying the roller *j* has become bent at its pivotal point and the spring 95

100

29 exerts pressure on the said roller *j*, but as soon as the roller *j* leaves the air box *e* the spring will straighten the knuckle-jointed arm which passes around the axle *p* until it again reaches the paper and the air box has opened the paper out.

The roller *j* acts on the sheet some little distance from its edge so that the sheet is gripped from the point of contact with the roller and the edge of the air box, the front of the sheet being sufficiently far from the roller to be gripped by the rollers 27, and the band *v* before the roller *j* leaves the air box. The rollers *j* are frictionally held in their bearings and in moving around get a slight revolution by action against levers 26 to as to expose a fresh surface for action on the next sheet.

It will be apparent that the spring controlled knuckle-jointed feed rollers *j* when in operation move in a direction over the pile of paper and are caused to grip the top sheet as the jets of air lift said top sheet and force the same against the said feed rollers *j*, causing the sheet to adhere to the rollers and at the same time the film of air enters from the air box *e* between the top sheet and its neighboring sheet, and in consequence the said top sheet can be moved by continued operation of the rollers *j*, which are moved by the shaft *p* without in any way drawing the neighboring sheet with it, and as the operation of the machine is continued a successive feed of single sheets is insured.

Two arms *l*, *l* are arranged over the pile of papers having the bars *q* to prevent the top sheet from being blown too high from the pile by the action of the air jets, and these arms *l*, *l* are hinged at *m* to depending legs *n* of arms *m'*, which are forked at one end for being positioned between the shiftable collars *x* arranged on the shaft *y*, the bent portions resting on the shaft *p*. The arms *l* are hinged for the purpose of enabling them to be lifted clear of the paper, when desired, and by moving the collars *x* sidewise the arms *l*, *l* can be positioned to the feed table *c*, to suit the pile of paper. The air supply pipe *g* has a branch *r* which extends across the sloping table *s* upon which the paper slides to the printing cylinder and air nozzles *t*, *t*, *t* are fitted to this branch, the air supply being regulated by a tap *u*. Jets of air issue from these nozzles onto the surface of the sheet of paper which is traveling down the endless bands *v* on the table *s* for firstly holding down said sheet in close contact with the bands, and secondly, to pass under the back edge of the preceding sheet and partly lift it off the bands so that it will be free to come square against the stop *w* ready for the grippers to take the sheet for the printing operation in the usual way.

The chain 1 is in gear with a wheel not shown on the machine, and actuated either directly or indirectly from the prime mover, 65 this chain 1 meshing with a pinion 2 on a shaft 3 journaled in bearings 4 on the standards *b*. On one end of the shaft 3 is mounted two chain wheels 5 and 6, the wheels 5 gearing by a chain 7 with a sprocket wheel 8 revolving on a fixed shaft 9. This wheel 8 is in connection with a sprocket wheel 10 which meshes with a pinion 11 on the shaft *p* for operating the same. On the other end of the shaft *p* is affixed a cam 12 which acts against a roller 13 on a lever 14 which is pivoted on the shaft *i* which carries the arms *h* having the air box *e* so that the air box *e* is operated. On the shaft *p* is mounted another cam 15 which operates a lever 16, this being pivoted 80 at 17 to the standard *b* and carrying at its free end a rod 18, having at its lower end a nose 19 for engaging a ratchet wheel 20, which operates a chain 21 attached to the guides *d* supporting the table *c* so that each 85 time the cam 15 operates the lever 16, the rod 18 will turn the wheel 20 one tooth.

22 is a pawl for preventing return of the wheel 20.

The wheel 6 is connected by endless chain 90 23 with a pinion 24 on the roller 25 which carries the endless band *v*.

Having thus described the invention, what is claimed is:—

1. An appliance for feeding sheets of paper 95 to printing machines, comprising a movable air supply box arranged to supply air to the edge of the pile of paper, a feed supply pipe communicating with the said box and having means for automatically shutting off the supply of air to the same when in its lowermost position, a frictional roller for engaging the topmost sheet of paper to withdraw the same from the pile, and cam mechanism for raising and lowering the supply box and for actuating the feed roller.

2. An appliance for feeding sheets of paper to a printing machine comprising an oscillating air supply box arranged to supply to a pile of paper to separate the uppermost sheets an air blast, an air supply pipe communicating with said box and adapted to automatically cut off the supply of air when the said box is in its lowermost position, a frictional roller engaging the topmost sheet of 110 paper to withdraw the same from the pile, mechanism for actuating the supply box and the frictional roller, and a fixed means for controlling the separation of the uppermost sheets of the pile of paper.

3. The combination of a feed table and a support for a pile of paper sheets, a sheet transferring device movable from the pile to the feed table, means for directing an air

blast between the forward edges of the uppermost sheets of paper for separating the same, and an air supply pipe coöoperative with said means and having an automatic valve adapted to shut off the supply of air to the air blast means when the same is in its lowermost position, means for operating the transferring device and said air blast means.

In testimony whereof I have hereunto set my hand in presence of two subscribing witnesses.

FREDERICK WILLIAM VICKERY.
